UNITED STATES PATENT OFFICE.

GEORGE E. DRUM AND JAMES H. SKITT, OF PHILADELPHIA, PENNSYLVANIA, ASSIGNEES TO ROBERT P. SMITH AND GEORGE E. DRUM, OF PHILADELPHIA, PENNSYLVANIA, COPARTNERS TRADING UNDER THE FIRM-NAME OF SMITH, DRUM AND COMPANY, OF PHILADELPHIA, PENNSYLVANIA.

CIRCULATING ROTARY DYEING-MACHINE.

1,125,497.

Specification of Letters Patent.

Patented Jan. 19, 1915.

Application filed April 14, 1914. Serial No. 831,703.

To all whom it may concern:

Be it known that we, GEORGE E. DRUM, a citizen of the United States, and JAMES H. SKITT, a subject of the King of England, residing at Philadelphia, in the county of Philadelphia and State of Pennsylvania, have invented certain new and useful Improvements in Circulating Rotary Dyeing-Machines, of which the following is a specification.

The invention has for its object to provide means for circulating the dye liquor in the vat, and consequently through the goods, in two directions, whereby a more uniform dyeing of the goods is accomplished than by those machines wherein the dye-liquor remains in a quiescent state.

A further object is to provide means for operating the goods containing cylinder and the dye liquor circulating means in given directions during certain stages of the treatment of the goods and to reverse these directions of movements during alternate stages, the changes from forward to reverse directions of movements being effected either manually or automatically.

With these and other objects in view, reference will be had to the accompanying drawings forming a part of this specification and wherein like characters of reference designate corresponding parts throughout the several views, in which:

Figure 1 is a top plan view of the invention, parts of the gearing being omitted for clearness, Fig. 2 is a vertical sectional view therethrough on the line 2—2, Fig. 3 is a vertical sectional view through Fig. 1 on the line 3—3, Fig. 4 is a view in side elevation, with part of the gearing broken away in section, Fig. 5 is a view in vertical section through Fig. 4, Fig. 6 is a top plan view of the gearing, Fig. 7 is a view in elevation of Fig. 6 viewed from the left-hand side, Fig. 8 is a view in elevation of Fig. 6 viewed from the front side, and Fig. 9 is a view in elevation of Fig. 6, viewed from the right-hand side.

The dye vat comprises two spaced parallel sides 1 connected by a round bottom 2, and within the sides are journaled the ends of

the shaft 3 of the cylindrical goods container. The latter is constructed preferably of imperforate end walls 4, perforated outer cylindrical wall 5, and perforated radial partitions 6, 7, 8, 9, all regularly spaced and dividing the cylinder into four goods compartments A, B, C, D, for which latter suitable doors, such as the one 10 of Fig. 1 may be provided to permit the goods to be put into and taken out of the several compartments. Between the bottom 2 of the vat and the outer cylindrical wall 5 of the goods cylinder is provided a partition 12 extending from one side wall of the vat to the other. The lower end of this partition terminates at a point substantially adjacent an imaginary perpendicular line drawn through the axis of the cylinder. The lower portion of this partition 12 has substantially the same curvature as the goods cylinder, and its upper portion is relatively straight and diverges from the outer wall 5 of the goods cylinder, its upper end terminating below an imaginary horizontal line drawn through the axis of the goods cylinder. When the dye liquor is at its normal height in the vat, its level is substantially on a line with the axis of the goods cylinder, and between the cylinder 5 and the upper right-hand side of the vat bottom, and, with its axis substantially in this same liquid level line, is mounted a circulating paddle 14, the blades thereof, which may be of any suitable number, being attached suitably to a shaft 15. When the goods cylinder and the circulating paddle operate in a forward direction, by means to be later described, their directions of movement will be as indicated by the arrows E and F respectively, and the consequent circulation of the dye liquor will be in the directions of the arrows G and H, the arrows to be observed in Fig. 5. Upon reversal of the operating mechanism, these several respective directions of movement and of circulation are reversely to the directions indicated by said arrows. In their operation, it will be observed that the paddle blades 14 barely clear the upper end of the partition 12, and thereby instead of the paddle being merely an agitator it forms 100

with the partition a positive liquid propelling or pumping means incorporated in the vat structure.

The gearing for accomplishing the above movements of the goods cylinder 5 and the circulating paddle, comprises a main shaft 20 and a reversing shaft 21 parallel therewith, both being suitably journaled in bearing brackets 22 and 23 respectively on the 10 plate 24, and the said plate being suitably attached to one of the sides 1 of the vat. To the main or pulley shaft 20 is keyed the pulley 25 and pinion 26, and adjacent this pulley and close on the main shaft 20 is an 15 intermediate pulley 27. Beside this pulley 27 is another pulley 28 loose on the main shaft and keyed to a pinion 29 also loose on the main shaft, and on the inner end of the main shaft is keyed a pinion 30. To the reversing shaft 21 are keyed pinions 31, 32, and 33, the first two being adjacent each other, and the larger one 31 meshing with pinion 26 of the main shaft. Intermediate 25 the pinion 32 of the reverse shaft and the pinion 29 of the main shaft and in mesh therewith is a pinion 34 loose on a stud 35. To the paddle shaft 15 is keyed or otherwise affixed a pinion 36 which meshes with the pinion 30 of the main shaft. On the goods 30 cylinder 5 is provided a gear ring 37 which meshes with the pinion 33 of the reversing shaft 21. The power belt (not shown) when the machine is running idle, runs on the intermediate free pulley 27, and for 35 shifting it to the forward drive pulley 25 or to the reverse drive pulley 28, a shipper bar 38 with fork 39 is provided. The shipper bar 38 is endwise slidable in spaced supporting brackets 40 and 41 and is provided with stops 42 and 43 for engagement with opposite sides of the bracket 40. For locking the shipper bar in an intermediate 40 position, a notch 44 is provided in the upper edge thereof and a detent 45 carried as an extension of a weight arm 46 enters into locking engagement therewith. The weight arm 46 is pivoted at its lower end at 49 to the supporting bracket 40 and at its upper end carries a ball weight 50. To the handle 45 of the shipper bar 38 is provided an upright arm 52 which is connected by a horizontal link 53 with a crank arm 54 fast on a rock-shaft 55, the latter being journaled in bearing fork 56 forming a part of the bearing bracket 23. To the opposite end of this rock-shaft is affixed a crank arm 57 having connection 57' with another crank arm 58 of a control rock-shaft 59, which latter is suitably mounted on the side of the vat and extends within a point where its crank handle 60 may be conveniently grasped by an operator. Loose upon this shaft 55 is a pinion 61 meshing with a worm 61' on the reversing shaft 21, and the hub 65 of the pinion 61 is provided with a lug 62,

which, as the pinion 61 is moved one way or the other by the operation of the reversing shaft engages with one or the other sides of a lug 63 provided on a segmental weight arm 64 to move the weight arm 64 up to and slightly over dead center, when the weight arm, being loose on the shaft 55, quickly falls by gravity to the completion of its movement in one or the other directions. This weight arm has an adjustable weight 65, and on its side opposite to the one bearing the lug 63 and at its front and rear ends are stop extensions 66 and 67, better illustrated in Fig. 6. Between these stops 66 and 67 is confined a crank arm 68 fast on the rock shaft 55. The fall of the weight arm 64 by its gravity after passing over dead center causes one or the other of its stop extensions 66 or 67 to engage with the crank arm 68, thereby giving a quick throw to the latter, and thereby giving a similar quick rocking movement to the shaft 55, which movement is transmitted through the crank arm 54, link 53 and upright arm 52 to the shipper bar 38. The result is a quick shipping of the belt from the pulley 25 to the pulley 28 or vice versa as the case may be, said movement under action of the weight arm being limited by the said stops 42 and 43 on the shipper bar encountering the sides of the bracket 40. This shipping of the belt from pulley 25 to pulley 27 results in automatic alternate forward and reverse rotation of the goods cylinder 5 and circulating paddle 14, and when it is desired to stop the same to change the goods, the belt must be shipped manually by moving the shipper rod 38 either directly by hand or through the medium of the control shaft 59 to an intermediate position, where it may be locked by the operator throwing over the weight arm 46 to cause its detent 45 to engage in the notch 44 of the shipper bar. In like manner, it will be seen that inasmuch as the shaft 55 is free from key with the pinion 61, it may be rocked manually through the medium of the side control shaft 59 to throw the shipper mechanism and consequently the belt so that the latter at any stage in the operation of the machine can be changed from one to the other of any of the three pulleys 25, 27, and 28. It is to be understood, of course, that the detent 45 in the normal operation of the machine under automatic action is in its disengaged position with respect to the shipper bar notch. In the forward drive of the machine, the belt is shifted from the idle pulley 27 to the pulley 25, by means and in the manner already described, and motion is imparted therefrom through main shaft 20 and its keyed pinion 26 to the large pinion 31 of the reverse shaft 21 and through the rotation of said reverse shaft 21 to the pinion 33, which latter being in mesh with

the cylinder gear ring 37 causes forward rotation of the goods cylinder 5 in the direction of the arrow E, Fig. 5. Meanwhile, the rotation of the main shaft 20 causes rotation of its pinion 30, which being in mesh with the paddle pinion 36, causes rotation of the paddle 14 in the direction of the arrow F, Fig. 5. In the reverse drive of the machine, the belt is shifted initially by manual means as already described from the idle pulley 27 to the reverse pulley 28, or subsequently to a forward driving stage from the forward drive pulley 25 to the reversing pulley 28 either manually or automatically through the means and in the manner already described. Motion is then imparted from the pulley 28 direct through its key to pinion 29 and therefrom through the intermediate pinion 34 to the pinion 32 of the reverse shaft 21. The consequent rotation of the reverse shaft 21 causes rotation of the pinion 33, which latter being in mesh with the cylinder gear ring 37 causes reverse rotation of the goods cylinder 5 reversely to the direction indicated by the arrow E, Fig. 5. Meanwhile, the rotation of the reverse shaft 21 causes rotation of the pinion 31 keyed thereto, and this pinion 31 being in mesh with the pinion 26 which is keyed to the main shaft 20 causes reverse rotation of the main shaft 20 and corresponding rotation of the pinion 30 on the end thereof. The paddle wheel pinion 36 being in mesh with the pinion 30, the paddle is caused to rotate reversely to the direction of the arrow F, Fig. 5.

The operation of the apparatus, and the effect thereupon of the mechanism described, is as follows: The goods being in place in the cylinder 5, the cylinder and paddle are caused to rotate forwardly, that is, in the directions indicated by the arrows E and F respectively in Fig. 5. As the cylinder rotates, the dye liquor is circulated through its compartments successively substantially in the direction of the arrow H, in Fig. 5. The dye liquor as it clears the lower end of the partition 12 is drawn upwardly between said partition 12 and the vat bottom 2 by the paddle and is again forced over the upper end of the partition 12 back into the vat. This continues as long as the mechanism rotates forwardly, it being clear that the dye liquor passes through the goods in but a single direction. Upon reversing the movements of the goods cylinder and paddle, the dye liquor is drawn reversely to the arrow H toward the paddle and then forced down the passage between the partition 12 and vat bottom 2 reversely to the arrow G. Clearing the lower end of the partition 12, the dye liquor is again drawn over the partition to the paddle, thereby causing the goods in the cylinder 5 to be impregnated from their opposite sides from which they

were formerly treated. This alternate forward and reverse operation of the mechanism with consequent forward and reverse circulation of the dye liquor results in flowing of the liquor through the goods from opposite sides in alternate stages, which is the present day advanced method of dyeing, and results in a very thorough and expedient saturation or dyeing of the goods, without wear and tear thereupon.

Importance is placed upon the curvature of the partition 12 conforming to the contour of the goods cylinder and being close thereto, there being no pockets in the partition between it and the cylinder where eddy currents or swirling of the dye liquor may set up to result in over or uneven dyeing of the goods adjacent the periphery of the goods container. Likewise, it is of importance that the goods cylinder or container be simultaneously reversible with the reversing of the circulation of the dye liquor. In apparatus where the circulation of the liquor reverses without corresponding reversal of the goods cylinder, the impregnation is more thorough during flow of the liquor in one direction than in the other for the reason that at one stage the liquor moves with the goods while at the other it moves contrary to the direction of movements of the goods. Hence, in one stage, the treatment is no better than a mere dipping of the goods, while in the other stage, the treatment amounts to an actual forcing of the liquor through the goods. In the present invention, both stages correspond in every respect.

What is claimed is:

1. In a dyeing apparatus, a vat, a rotary goods container, a partition in the vat between the container and the wall of the vat, means for circulating the dye liquor around the partition, and means for reversing the flow of the liquor around said partition and for reversing the movement of the container.

2. In a dyeing apparatus, a vat, a rotary goods container, a partition in the vat between the container and the wall of the vat, means for circulating the dye liquor around the partition, and means for simultaneously reversing the flow of the liquor around said partition and the movement of the container.

3. In a dyeing apparatus, a vat, a rotary goods container, a partition in the vat between the container and the wall of the vat, means for circulating the dye liquor around the partition, and means for automatically and simultaneously reversing the flow of the liquor around said partition and the movement of the container.

4. In a dyeing apparatus, a vat, a goods container therein, a partition between the container and the wall of the vat and being

- close to and substantially conforming to the contour of the container, and automatic means for circulating the dye liquor alternately in reverse directions around said partition and through said container.
5. In a dyeing apparatus, a vat, a rotary goods container therein, a partition between the rotary container and the wall of the vat and being close to and substantially conforming to the contour of the container, means for rotating the container, means for circulating the dye liquor around said partition and through the container, and means for automatically and simultaneously reversing the direction of movement of the container and of the flow of said dye liquor.
6. In a dyeing apparatus, a vat, a rotary goods container therein, a partition between the rotary container and the wall of the vat around which and through the container the dye liquor circulates, means for alternately reversing the flow of the liquor through the same goods in the container in determinate periods of even duration.
- 25 7. In a dyeing apparatus, a vat, a rotary goods container therein, means for circulating the dye liquor through the goods in the container, means for rotating the container, and automatic means for reversing both of said means whereby the dye liquor will flow through the same goods alternately in reverse directions in periods of even duration.
8. In a dyeing apparatus, a vat, a rotating goods container therein, means for circulating the dye liquor through the goods in one direction, and means for automatically and means for manually reversing the circulation of the dye liquor and the direction of rotation of the container simultaneously.
- 35 9. In a dyeing apparatus, a vat, a rotating goods container therein, means for circulating the dye liquor through the goods in the container in one direction, automatic means for simultaneously reversing the direction of circulation of the dye liquor and movement of the container, and means for manually effecting this said reversal at any stage independently of the automatic means.
- 45 10. In a dyeing apparatus, a vat, a rotary goods container therein, means for circulating the dye liquor through the goods container, automatic means for reversing the direction of circulation of the liquor, and means for manually effecting this said reversal at any stage independently of the automatic means.
- 55 11. In a dyeing apparatus, a vat, a rotating goods container, means for rotating the container, means for circulating the dye liquid through the goods container, automatic means for reversing the direction of rotation of the container, and means for manually effecting this said reversal at any stage independently of the automatic means.
- 65 12. In a dyeing apparatus, a vat, a goods container therein, a partition between the container and the wall of the vat around which the dye liquor flows, and liquid propeller means above and coacting with the upper end of the partition to circulate the dye liquor.
13. In a dyeing apparatus, a vat, a goods container therein, a partition being throughout close to the container and located between the latter and the wall of the vat and around which partition the dye liquor flows, and a liquid propeller above and coacting with the upper end of the partition to circulate the dye liquor.
- 75 14. In a dyeing apparatus, a vat, a goods container therein, a partition located between the container and the wall of the vat and around which the dye liquor circulates, and a rotary liquid propeller having its lower portion only projecting below the normal liquid level and coacting with the upper end of the partition to circulate the dye liquor.
- 80 15. In a dyeing apparatus, a vat, a goods container therein, a partition between the same and the wall of the vat around which the dye liquor circulates, a liquid propeller coacting with the upper end of the partition to circulate the dye liquor, and means for rotating the container and liquid propeller alternately in reverse directions for determinate periods.
- 90 16. In a dyeing apparatus, a vat, a goods container therein capable of rotation in reverse directions; means capable of rotation in reverse directions for circulating the dye liquor through the goods container; operating means for the container and said first named means; control means for rendering the operating means inactive or forwardly or reversely operative, automatic means for effecting the control means to render the operating means alternately forwardly and reversely operative, and manual means for effecting the control means to render the operating means selectively inactive or forwardly or reversely active at any stage.
- 100 17. In a dyeing apparatus; a vat; a rotary goods container; means for circulating the dye liquor through the container; control means for rendering the container and circulating means inactive and for imparting forward and reverse movements thereto to permit the dye liquor to flow through the goods container in one or the other directions in equal stages, and means whereby said control means may be actuated automatically to cause alternate forward and reverse actions of the mechanisms subject thereto; and means whereby the control means may be actuated to selectively cause inactive, forward or reverse actions of the mechanisms subject thereto.
- 115 18. In a dyeing apparatus, a vat, rotary
- 120
- 125
- 130

goods container therein capable of rotation in reverse directions, rotary circulating means for causing flow of the dye liquor through the container, gearing comprising elements for causing inactivity or forward or reverse driving of the container and circulating means, means for applying driving force separately to said elements, and a rock shaft for actuating said applying means, a pinion loose on said shaft and reversibly actuated by said gearing, a weight arm loose on said shaft and adapted to be oscillated on said shaft by said pinion, and an arm fixed to said shaft and adapted to be moved

by the fall of the weight arm after passing 15 dead center to quickly rock said shaft; and manual means whereby said shaft may be rocked selectively in either direction independently of the weight lever, pinion and operating means therefor. 20

In testimony whereof we affix our signatures in presence of two witnesses.
